INDEX TAB

Lurene A. Johnson and William A. Doble, Jr.,
San Francisco, Calif.

Application June 27, 1939, Serial No. 281,384

1 Claim. (Cl. 40—16)

This invention relates to an index tab to be used where it is desirable to index cards, sheets or other elements.

It is one of the principal objects of this invention to disclose a simple and effective index tab which may be easily and inexpensively manufactured and which may be mechanically attached to the element to be indexed without the application of glue or other adhesive materials.

10 A further object is to provide such an index tab with gauging means for correctly locating the tabs onto their respective elements to be indexed and which will further act to effectively clamp the tabs to their elements preparatory to and during 15 the fastening of the tabs thereto by stapling or other mechanical means.

20 A further object is to provide an index tab having one front edge extending beyond the other edge to facilitate the application of the tab to the element to be indexed.

25 A further object is to form a relatively long strip of tab material by longitudinally folding back upon itself a ribbon of transparent material and applying gauging means therealong to form 30 a pocket between the fold and gauging means and an open ended slot between the gauging means and free ends of the folded strip.

35 A further object is to mount an index member within the pocket of the strip having lines for 30 guiding the cutting of the strip into individual tabs of desired lengths.

These and other objects and advantages will 40 become apparent as the nature of the invention is more fully understood from the following description and accompanying drawing, wherein is 45 set forth what is now considered to be a preferred embodiment.

It should be understood, however, that this 45 particular embodiment of the invention is chosen principally for the purpose of illustration, and that variations therefrom in details of construction or arrangement may accordingly be effected and yet remain within the spirit and scope of the invention as the same is set forth in the appended 50 claim.

In the drawing:

Fig. 1 illustrates a fragmental plane view of the index strip.

Fig. 2 illustrates a tab cut from the strip and applied to a sheet or card to be indexed.

Fig. 3 illustrates a perspective view of the fully mounted tab.

Fig. 4 illustrates a fragmental plan view of a modified form of the invention.

55 Fig. 5 illustrates an end view of Fig. 4.

In the preferred embodiment of the invention a ribbon of transparent material 10 is longitudinally folded back upon itself as at 11 so that the upper side 12 of the strip will closely overlie the lower side 13. In folding the material it is preferable to make the two sides of unequal length as shown in Figs. 1, 3, 4 and 5, wherein the underside 13 is made slightly longer than the upper side 12. The purpose of this difference in length is to provide an extending edge or lip which will 15 greatly facilitate mounting the tab onto the element to be indexed.

After the ribbon has been folded in the manner above described, gauging means 14 may be applied therealong to form a longitudinal pocket 15 15 between the fold and gauging means and a longitudinal open ended slot, between the gauging means and free ends of the strip.

The gauging means 14 may be in the form of staples and applied by any type of standard 20 stapling machine commonly sold by stationery houses or in large production the staples may be applied to the strip by an automatic machine. It is to be understood that in place of the staples 14 rivets 17 as shown in Figures 4 and 5 may be 25 used instead, or any other appropriate form of mechanical clamping means.

It is preferable however to use staples formed of flat wire as illustrated most clearly in Fig. 3.

After the gauging means have been applied to 30 the strip, an index member 16 may be inserted in the longitudinal pocket 15.

The index member is preferably provided with 35 indicating lines 18 which intercept the spacing between the gauging means to guide the cutting of the strip into individual index tabs.

In practice it has been found convenient to use staples for the gauging means 14 which are approximately a quarter of an inch in length and spacing the staples approximately one quarter 40 of an inch apart and spacing the index lines 18 approximately one half inch apart and centrally locating the index lines between the staples. In this way index tabs from one half inch in width to any width in multiples of one half inch may 45 be conveniently cut from the tab strip. The index member 16 may be made of a single strip of material as indicated in Figs. 4 and 5 at 16a or may be folded as shown in Figs. 2 and 3. The 50 advantage of using a folded index strip results in its tendency to spring apart and thus bind and clamp itself within the pocket 15. The index member may be directly used to note the index information thereon or the indexing information 55

may be typewritten upon a sheet of suitable paper and cut to fit into the tab pocket 15.

In Fig. 2 is shown an index tab 20 cut from the strip along the third index line 18 and thus according to the proportions above set forth, would be approximately one and one half inches in length, however, if a one half inch tab should be needed, it would be cut along the first index line 18, if an inch tab should be desired it would be cut along the second index line 18 and so on.

In the proportions above set forth tabs of one half inch will contain one of the gauging staples 14, tabs of one inch in length will contain two of the gauging staples 14 and a tab of one and one half inches in length as shown in Fig. 2, will contain 3 of the gauging staples 14 and so on.

The staples 14 tightly clamp the two side walls of the tab together and thereby longitudinally dividing the tab into the pocket 15 and the open slot 22 which is formed between the front portion 23 of the side wall 12 and the front portion 24 of the side wall 13. As will be noted in Fig. 3, the front portion 24 projects beyond the front portion 23 to provide the lip 26 which is made use of to spread the two ends 23 and 24 apart in order to enable the tab to be readily mounted upon the element to be indexed. In other words the lip portion 26 will be first brought into engagement with the element 21 spreading apart the portions 23 and 24 whereupon the element 21 can be slid therein until the front edge 27 of the element 21 registers with the gauging means 14 and in this way correctly positioning the tab on the element and thereby insuring the same alignment for all of the tabs.

Due to the clamping effect of the gauging staples 14, the ends 23 and 24 will act to clamp the tab in its adjusted position on element 21 and will so hold the tab until it is mechanically attached thereto.

With a tab mounted on element 21, it may be mechanically fastened thereto by the staples 28 preferably of the same type as the gauging staples 14, however it is to be understood that rivets or other types of mechanical attaching means may be substituted for the staples 28. The staples or other types of mechanical attaching means may be applied with the usual stapling or rivet-

ing apparatus generally found in an office or by apparatus especially provided for the purpose.

The mechanically fastening means enables the tabs to be easily and quickly secured to their respective elements and eliminates the nuisance of employing an adhesive substance for this purpose.

In Fig. 2 the tab 20 is shown fastened to the element 21 by three staples 28 of the same size and type as employed for the gauging means. It is to be understood however, that a greater or lesser number of staples, rivets, etc. may be used for this purpose and also if staples are used they may be of a different size and type from that used for the gauging means.

An important advantage resulting from the use of the mechanical means for fastening the tabs to their elements resides in the ability to easily remove the fastening means thus permitting the tabs to be used over and over again.

The gauging means 14 act to confine the index member within the pocket 15 thereby preventing the slipping of this member out of position. It also tends to clamp the index member so that it will not readily slip from within the pocket 15.

In Figs. 4 and 5, those parts which correspond to the same parts in the other figures of the drawing have been given the same numbers with the letter *a* affixed thereto.

Having fully described the invention, it is to be understood that it is not to be limited to the details herein set forth, but the invention is of the full scope of the appended claim.

We claim:

An article of manufacture including a strip of transparent material longitudinally folded back upon itself, a plurality of staples arranged to form gauging means securely clamping the two side walls of the strip together at longitudinal intervals along a plane located a predetermined distance from the fold of said strip and an index member mounted in the pocket formed between the fold and gauging means, and said index member having transverse index lines arranged to indicate the cutting planes of the strip intermediate the positioning of said plurality of staples.
